US0D1012560S

(12) United States Design Patent (10) Patent No.: US D1,012,560 S
(45) Date of Patent: * Jan. 30, 2024

(54) CARPET

(71) Applicant: Yiwu Ligao Technology Co., Ltd,
YiWu (CN)

(72) Inventor: Linfei Chen, Yiwu (CN)

(73) Assignee: Yiwu Ligao Technology Co., Ltd.,
Yiwu (CN)

() Term: 15 Years

(21) Appl. No.: 29/844,990

(22) Filed: Jul. 3, 2022

(51) LOC (14) Cl. 06-11

(52) U.S. Cl.

USPC D6/590

(58) Field of Classification Search

USPC D5/57, 63; D6/582-583, 587-588, 592;

D12/203; D21/792

CPC A47G 27/0206; A47G 27/0225; A47G

27/0237; A63B 6/00; A47L 23/266
